UNITED STATES PATENT OFFICE.

FRED J. CROSS, OF ROCHESTER, NEW YORK, ASSIGNOR TO ROCHESTER STAMPING COMPANY, OF ROCHESTER, NEW YORK, A CORPORATION OF NEW YORK.

DESIGN FOR A BODY FOR COFFEE AND TEA POTS, PERCOLATORS, AND TEA-BALL POTS.

48,104.

Specification for Design.

Patented Nov. 9, 1915.

Application filed August 5, 1915. Serial No. 43,888. Term of patent 14 years.

To all whom it may concern:

Be it known that I, FRED J. CROSS, a citizen of the United States, residing at Rochester, in the county of Monroe and State of New York, have invented a new, original, and ornamental Design for Bodies for Coffee and Tea Pots, Percolators, and Tea-Ball Pots, of which the following is a specification and of which the accompanying drawing is a representation.

The drawing is an elevation of a coffee pot body showing my new design.

I claim:

The ornamental design for a body for coffee and tea pots, percolators and tea ball pots, as shown.

FRED J. CROSS.

Witnesses:

A. R. LORD,
FRED W. KEHR.
